SELF-EJECTING KEY

David E. Evans, Columbus, Ohio

Application April 29, 1933, Serial No. 663,552

14 Claims. (Cl. 70—9)

My invention relates to keys and has particular reference to a self-ejecting key comprising mechanism whereby the key will be ejected from a lock or mechanism it is adapted to control after it has effected either the locking or unlocking of the same depending upon the manner in which the mechanism is made and the use to which it is put.

An object of my invention is to provide an ejector mechanism associated solely with the key so that keys may be manufactured and used without the necessity for modification of the locks or other mechanism with which they are to be used.

15 A further object of my invention is the provision of a self-ejecting key readily insertable in a standard lock and automatically ejected from said lock when the tumblers engaging portions of the key are not in engagement with the tumblers 20 of the lock.

A still further object of my invention is to provide a self-ejecting mechanism and key of simple construction, inexpensive to manufacture, the said ejecting mechanism being of such design 25 that keys now in use can be modified without making the key bulky or unwieldy in use.

In the accompanying drawing, forming a part of this specification, I show preferred embodiments of my invention.

30 Fig. 1 is a side elevation, partly in section, showing the key assembled with its ejecting mechanism.

Fig. 2 is a sectional view of the line 2—2 of Fig. 1.

35 Fig. 3 is a perspective view of a lock casing of well known construction, showing the preferred form of my self-ejecting key about to be inserted therein, it being noted that in this disclosure the lock is assumed to be in locked position.

40 Fig. 4 is a side elevation, showing a modification of my self-ejecting key mechanism.

Fig. 5 is a sectional view on the line 5—5 of Fig. 4.

45 Referring to the drawing, wherein like numerals designate like parts, the numeral 6 designates the face plate of a lock of standard construction, for example the ignition lock of an automobile. The face plate 6 is provided with a key-hole through which the key is adapted to be inserted to lock or unlock the mechanism the key is adapted to control.

In the preferred form of my invention as shown in Figs. 1, 2 and 3, the key 7 is ridged or grooved or otherwise formed to operate the tumblers or 55 other parts of its associated mechanism. The

key 7 comprises a shank or body portion 8 and a handle 9 of usual construction. Most keys of this character have a circular aperture 10 in the handle 9 thereof for attachment to key rings etc. I propose to cut or form a slot or guideway 60 11 in the shank or body 8, said slot extending from the aperture 10 in the handle to within close proximity to the opposite end of the shank. A pin 12 extending longitudinally of said slot and disposed centrally thereof is fixed to one or both 65 ends of the key and together with the slot 11 form a guideway along which a lock engaging abutment member 13 is adapted to slide, the member 13 having an aperture therein adapted to slidably fit the pin 12. A coiled compression 70 spring 14 encircling the pin 12 is interposed between the closed rear end of the slot 11 and the abutment member 13 thereby normally retaining said abutment member within the longitudinal 75 limits of the tumbler engaging portions of the key shank.

The member 13 is provided with a reduced central portion 15 and the heads 16 are prevented from movement laterally of the key and thereby always retained in operating position. The coil 80 spring 14 and the pin 12 are of such dimensions that they are confined within the lateral planes of the key thereby providing a compact, neat mechanism no more bulky than keys without self-ejecting mechanism. The abutment member 13 may be cylindrical or square as choice 85 may dictate, but what I believe to be the preferred form is shown.

In assembling this form of my invention the abutment member 13 is placed within the aperture 10 and moved along the slot 11 to the forward end thereof, the spring 14 is placed within the slot between the member 13 and the opposite end of said slot and the pin 12 inserted in the aperture 125 of the handle 9, said pin being passed 90 within the spring and through the aperture of the member 13 whence the pin is soldered, or otherwise fixed at one or both ends, therefore assembly of the parts is very simple and easily 95 accomplished.

In operation, referring to Fig. 3, the key shank 8 is inserted in the key-hole of the face plate 6 and the shank pushed inwardly until the lock engaging portions are in position to actuate the mechanism. The key is then turned to unlock 100 105 said mechanism.

The inward movement of the key 7 causes the abutment member 13 to abut against the face plate 6 and the continued inward movement of the key forces the abutment 110

member rearwardly against the compression of the spring 14. When the key is turned to actuate the lock it cannot be withdrawn until it is returned to the initial position. As soon as the 5 key is returned to the initial position the spring 14 acting against the member 13 and the opposite end of the slot 11 functions to forcibly eject the key from the lock.

In the modified form of my invention as shown 10 in Figs. 4 and 5 the pin 12a is fixed to and slideable with the abutment member 13a, reliance being had in the heads of the abutment alone to prevent lateral displacement of said member. In order to confine the spring 14a within the slot 15 or guideway 11a the plates 17 are soldered or otherwise fixed to the handle of the key thereby forming a pocket 18 for the spring 14a. In assembly the member 13a is placed within the aperture 10a and slid along the slot after which 20 the pin 12a is fixed to the member 13a, the spring 14a installed, and the cover plates 17 affixed. The operation or use of the key being the same it will not be described.

While either the preferred or modified form of 25 my invention is capable of forcibly ejecting a key from any associated mechanism, it finds particular application with key controlled ignition and steering wheel locks used on automobiles. In such mechanisms it is customary to turn the 30 key to the unlocked position, the key being retained in the lock casing by the lock structure and cannot be withdrawn therefrom until moved to the locked position.

Motorists frequently turn the key to "off" 35 position of the ignition switch or locked position of the steering mechanism and inadvertently leave the key in the lock. My invention provides for ejection of the key into the hand of the operator immediately when the key is turned to 40 such position.

It is to be understood that the forms of my 45 invention shown and described are preferred embodiments and that various changes may be made without departure from the spirit of the invention or the claims.

What I claim is:

1. An ejector mechanism for keys comprising a slotted guideway in the key shank, a lock engaging abutment member slideable along said guideway and a spring interposed between said member and one end of said guideway for normally retaining the member within the longitudinal limits of the tumbler engaging portion of the key shank.

55 2. An ejector mechanism for keys comprising a guideway along the key shank, a lock engaging abutment slideable in said guideway, a portion of said member projecting laterally from the face of the key shank and a spring interposed between said member and one end of said guideway for normally retaining the member within the longitudinal limits of the tumbler engaging portion of the key shank.

3. An ejector mechanism for keys comprising, 60 a longitudinally extending closed slot in the key shank, a pin disposed centrally of said slot, a lock engaging abutment member slidably mounted on said pin and a spring encircling said pin and interposed between said member and one end of said slot for normally retaining the member within the longitudinal limits of the tumbler engaging portion of the key shank.

75 4. An ejector mechanism for keys comprising, a guideway in the key shank, a cylindrical lock 75 engaging abutment member projecting laterally

from said guideway and having a reduced central portion fitting said guideway, said member being adapted to slide along said guideway, and a spring interposed between said member and one end of said guideway for normally retaining the member within the longitudinal limits of the tumbler engaging portion of the key shank.

5. An ejector mechanism for keys comprising, a longitudinally extending guideway in the key shank closed at both ends, a pin disposed centrally of said slot, a lock engaging abutment member slideable in said slot and a spring encircling said pin and interposed between said member and one end of said slot for normally retaining the member within the longitudinal limits of the tumbler engaging portion of the key shank.

6. An ejector mechanism for keys comprising, a guideway along the key shank, a lock engaging abutment member slideable along said guideway, laterally extending cylindrical shaped portions on said member, and a spring interposed between said member and one end of said guideway for normally retaining the member within the tumbler engaging portion of the key shank.

7. An ejector mechanism for keys comprising, a longitudinally extending closed end slot in the key shank, a pin fixed to said key at one end of said slot, a lock engaging abutment member slidably mounted on said pin and guided by said slot, and a spring encircling said pin and interposed between said member and one end of said slot for normally retaining the member within the tumbler engaging portion of the key shank.

8. An ejector mechanism for keys comprising, a guideway, a member having a reduced central portion fitting and slideable along said guideway and a laterally projecting lock engaging portion, a spring positioned within said guideway and interposed between said member and one end of said guideway as and for the purpose set forth.

9. An ejector mechanism for keys comprising, a longitudinal slotted guideway formed in the key shank, a lock engaging abutment member slideable along said guideway, means preventing lateral movement of said member and means normally retaining said member within the longitudinal limits of the tumbler engaging portion of the key shank.

10. An ejector mechanism for keys comprising, a longitudinal guideway in the key shank, lock 125 engaging means projecting laterally from both sides of the key shank and slideable in said guideway and means normally retaining said member within the longitudinal limits of the tumbler engaging portion of the key shank.

11. An ejector mechanism for keys comprising, a longitudinally extending guideway, a lock engaging abutment member projecting outwardly from said guideway and slideable in said guideway, a pin fixed to said member and disposed centrally 135 of said guideway, a spring encircling said pin and interposed between said member and one end of said guideway as and for the purpose set forth.

12. An ejector mechanism for keys comprising, a longitudinally extending guideway, a member 140 slideable along said guideway and having a laterally projecting lock engaging abutment, a pin fixed to said member, a spring encircling said pin said spring being interposed between said member and one end of said guideway and means 145 preventing accidental disassociation of said spring from normal operating position.

13. An ejector mechanism for keys comprising, a longitudinal guideway in the key shank, a member 150 slideable along said guideway and having a lat-

erally projecting lock engaging abutment, a pin fixed to said member, a pocket in one end of said guideway and a spring encircling said pin, one end of said spring being seated in said pocket and the opposite end abutting said member to normally retain the member with the longitudinal limits of the tumbler engaging portion of key shank.

a guideway along the key shank, a lock engaging abutment member slidable along said guideway and having a portion projecting laterally from said guideway, a spring interposed between said member and one end of the guideway for normally retaining the member within the longitudinal limits of the tumbler engaging portion of the key shank.

14. An ejector mechanism for keys comprising
